UNITED STATES PATENT OFFICE.

WILLIAM H. ERMENTROUT AND EDWIN H. ZACHARIAS, OF READING, PENNSYLVANIA.

MACHINE FOR PRESSING FABRICS.

1,147,383.

Specification of Letters Patent. Patented July 20, 1915.

Application filed December 26, 1913, Serial No. 808,895. Renewed March 16, 1915. Serial No. 14,771.

To all whom it may concern:

Be it known that we, WILLIAM H. ERMENTROUT and EDWIN H. ZACHARIAS, citizens of the United States, residing at Reading, in the county of Berks and State of Pennsylvania, have invented certain new and useful Improvements in Machines for Pressing Fabrics; and we do hereby declare the following to be a full, clear, and exact description of the same, reference being had to the accompanying drawings, forming part of this specification, and to the figures and letters of reference marked thereon.

This invention has for its object to provide an improved textile press which is especially well adapted for pressing hosiery, although competent for use in pressing other articles or materials of a textile character.

The invention consists in certain novel details of construction and combinations and arrangements of parts, all as will be hereinafter described and pointed out particularly in the appended claims.

Referring to the accompanying drawings, Figure 1 is a side elevation of a textile press embodying the present improvements; and Fig. 2 is a top plan view of the same.

Like letters of reference in the several figures indicate the same parts.

The machine embodies in its construction a very substantial frame which is conveniently composed of end portions A and A' and an intermediate or bridge-like portion A², the end portions A and A' being adapted for the support of relatively large drums or rollers B and C, respectively. The drum B is of metal with a polished or smooth periphery, and is adapted to be steam-heated through the medium of a steam pipe b which may be introduced through the journal at one end of the drum. At the opposite end the drum B is provided with a driving mechanism which conveniently consists of a worm gear indicated at D in dotted lines in Fig. 1, with which meshes a worm D' on the lower end of a shaft D². At its upper end the shaft D² carries a worm wheel D³ meshing with a worm D⁴ (both shown in dotted lines in Fig. 2) and the worm D⁴ is mounted on a shaft D⁵ receiving motion from a motor indicated at E. With this arrangement of drive gearing a very small

motor may be employed and at the same time the drum may be rotated at a very uniform rate and at sufficient speed to perform all of the functions for which it is intended. Passing around the two drums B and C is a belt H preferably of steel, although other material may be employed, and the tension of this belt is made adjustable by mounting the drum C in bearings C' adjustable in the frame A' through the medium of adjusting screws C².

The lower reach of the belt between the drums, travels over the bridge portion A² of the frame, and under a table I, adapted to support the hosiery or articles to be pressed. The machine is designed to receive said articles on the inner side of the belt as distinguished from ironing or pressing machines in which the articles are received and carried on the outer side of the belt. The articles which are first piled on the table I are spread by the attendant and fed to the belt preferably under a smoothing roller K journaled in swinging arms k and from which the articles pass into the bight between the steam heated drum B and the inner surface of the belt. Between the smoothing roller K and the drum B there is preferably arranged a spray or dampening pipe L through which moisture may be admitted and ejected into contact with the articles before they are subjected to the pressing operation.

The articles being pressed are carried around the periphery of the drum and between the drum and belt, but before being allowed to escape or being discharged therefrom they are preferably subjected to a final relative heavy pressure imparted by a pressure roller M mounted in the upper portion of the frame A and adjustably and yieldingly advanced by the springs and adjusting screws m and m' respectively. After passing up over the top of the drum they are caught by the upper edge of an inclined chute N and conducted thereby down to a receiving table O located to one side of the table I, thus bringing the articles back into proximity to the point where they were delivered to the machine. Obviously one attendant may be located on each side of the machine, if so desired, inasmuch as both ta-

bles are accessible from both sides of the machine and either may distribute the articles to the belt for being pressed or remove the finished articles from the table O.

5 Obviously, the frame of the machine will be subjected to considerable pressure owing to the fact that the articles being pressed are passed in between the belt and drum, and to resist such pressure it is preferred to brace 10 the two ends of the frame by longitudinal braces P located above or in proximity to the bearings of the drums. Such braces furthermore serve as convenient guards to prevent the attendants from coming into 15 contact with the edges of the upper reach of the belt. The lower reach of the belt is effectually screened by the tables I and O, save at the point where the articles are fed thereto immediately in front of the smoothing 20 roller K.

In operation, articles from the table I are spread by the attendant and fed to the belt where they will be caught under the smoothing roller K. A general straightening out 25 of the articles will be effected by the smoothing roller and the articles will then pass under the dampener, and finally into the pressure zone, between the periphery of the steam heated drum and steel belt, which will 30 effectually press the same, a final pressure being imparted by the yielding pressure roller M just before the articles are carried over the top of the drum and delivered to the chute. The articles will be stripped 35 from the drum by the upper edge of the chute, and will travel by gravity down the chute and onto the receiving table, from which they can be removed, as desired.

Obviously, the machine is of such character 40 that the pressing of hosiery, etc., may be performed without the use of press paper and without the use of press boards, ordinarily employed. A surface finish will be imparted which may be controlled by the 45 character of the surface of the metal parts with which the articles come in contact.

Having described our invention, what we claim as new and desire to secure by Letters Patent of the United States, is,—

50 1. In a machine for pressing fabrics, the combination with a pair of relatively large drums, means for heating one of said drums, and means for rotating the same, of a belt including both of said drums and forming 55 reaches therebetween, the lower reach of said belt having its inner surface exposed whereby articles to be pressed may be placed on the inner side of the lower reach of said belt whereby they will be carried around between the heated drum and belt.

60 2. In a machine for pressing fabrics, the combination with a heated drum, and a co-operating drum spaced therefrom, of a belt passing around said drums and forming 65 reaches therebetween spaced one from the

other, the lower reach of the belt having its inner face exposed, a table for the articles located between the drums and within the reaches of the belt, and a preliminary straightening roller coöperating with the 70 inner face of the belt in proximity to the heating drum, whereby articles may be placed on the inner face of the belt, pressed between said inner face and the periphery of the drum and discharged into the space 75 between the drums and between the reaches of the belt.

3. In a machine for pressing fabrics, the combination with a heated drum and a co-operating adjustable drum spaced one from the other, of a belt passing around said drums and forming separated reaches therebetween, of means for preliminarily straightening the articles to be pressed, located on the inner side of the belt in proximity to the 80 heated drum, and an inclined chute extending from the upper portion of the heated drum downwardly between the reaches of the belt whereby articles may be pressed by being placed on the inner surface of the belt 90 and passed around the heated drum between the belt and drum, being thence discharged down the inclined chute and away from the point where placed on the belt.

4. In a machine for pressing fabrics the 95 combination with a heated drum and a co-operating drum spaced one from the other, of a belt passing around said drums and forming separated substantially straight reaches therebetween, a preliminary straightening roller journaled in proximity to the heated drum and coöperating with the inner 100 face of the belt to preliminarily straighten articles fed to said inner face, and a spring-pressed roller bearing on the exterior face of 105 the belt in proximity to the upper side of the heated drum.

5. In a machine for pressing fabrics, the combination with a heated drum and a co-operating drum spaced therefrom, of a belt 110 passing around said drums and forming substantially straight, widely separated reaches therebetween, whereby a sufficient area is left intermediate the drum and reaches of the belt for the application and removal of articles to and from the inner face of the belt, an inclined chute for stripping the articles from the upper side of the drum, and a table located over the lower reach of the belt for supporting articles out 115 of contact therewith.

6. In a machine for pressing fabrics, the combination with a heated drum, and a co-operating drum spaced therefrom, of a belt 120 passing around said drums and forming widely separated reaches therebetween, a table for the articles to be pressed, extending over the inner surface of the lower reach of the belt, a preliminary straightening roller intermediate said table and heated drum, a 125 130

dampener extending over the inner surface of the belt intermediate the straightening roller and drum, a spring-pressed pressure roller coöperating with the outer surface of the belt, an inclined chute located intermediate the drums and belt reaches for stripping the pressed articles from the heated drum, and a

table for receiving the articles passing down the chute.

WILLIAM H. ERMENTROUT.
EDWIN H. ZACHARIAS.
